(57) **CLAIM**

The ornamental design for a barbecue tool utensil handle, as shown and described.

DESCRIPTION

FIG. 1 is a left-side elevational view of a barbecue tool utensil handle showing our new design, the right-side being a mirror image thereof;

FIG. 2 is a top plan view of the handle of FIG. 1;

FIG. 3 is a bottom plan view of the handle of FIG. 1;

FIG. 4 is a front-end view of the handle of FIG. 1; and, FIG. 5 is a rear-end view of the handle of FIG. 1.

The broken lines are for illustrative purposes only and form no part of the claimed design.
